QUICK EXIT SEPARABLE FASTENER

Louis H. Morin, Bronx, N. Y.

Application February 18, 1946, Serial No. 648,473

10 Claims. (Cl. 24—205.11)

1

This invention relates to separable fasteners of the type and kind wherein means is provided for quickly separating the stringers of separable fasteners, while at the same time, providing a stop for the slider in normal uses of the fastener. More particularly, the invention deals with the provision of a nylon or other spring like plastic nubbin on an end stop link whereby a slider may be forceably moved over the stop link in providing a quick pull apart separation of the stringers as and when desired. The novel features of the invention will be best understood from the following description when taken together with the accompanying drawing, in which certain embodiments of the invention are disclosed, and in which the separate parts are designated by suitable reference characters in each of the views, and in which:

Fig. 1 is a face view of the upper end portion of a pair of stringers, showing the slider in section and with the parts in a normal stop position.

Fig. 2 is a partial section on the line 2—2 of Fig. 1 on an enlarged scale and showing only one stringer and omitting background illustrations; and

Fig. 3 is a view similar to Fig. 2, showing only a part of the construction and showing a modification.

In Fig. 1 of the drawing I have shown at 10 and 11 upper end portions of a pair of stringers to the beaded edges 12 and 13 of which are attached scoops 14 and 15, providing normal coupling engagement of the stringers. The scoops 14 on the stringer 10 extend for a greater length beyond the end scoop 15' of the stringer 11 so that the slider 16 can extend to an end stop 17 on the stringer 10.

On the shorter stringer 11 are provided two special links, scoops or elements 18 and 19. The link 18 forms what may be termed a stop link, and has a pair of finger portions 20 adapted to extend between spaced scoops 14 of the stringer 10 in the manner illustrated. The special scoop 19 operates as a guide scoop and has a pair of fingers 21 also free to extend between the scoops 14 of the stringer 10 as and when the slider 16 is forceably moved in the direction of the stop 17.

Considering Fig. 2 of the drawing, it will appear that the slider 16 or the spaced top and bottom walls 22 and 23 thereof have at one side recesses, as at 24 and 25. These recesses open through the wide end 26 of the slider, as seen in Fig. 1, and terminate at shoulder portions 27 and 28,

2

the shoulder portion 28 being indicated in Fig. 1 of the drawing. These shoulder portions are short of the contracted or single channelled end 29 of the slider. It will be understood that the dimensions of the recesses 24 and 25 and the shoulders 27 and 28, as appearing in Fig. 2 of the drawing, are exaggerated for sake of clarity.

The stop link or scoop 18 has an aperture 30 extending therethrough which also pierces the tape 11 or the beaded edge 13 thereof, and in this aperture is arranged a stop pin or nubbin 31 which extends slightly beyond upper and lower surfaces of the link or scoop 18 and sufficient to enter the recesses 24 and 25 and engage the shoulders 27 and 28 to check normal closing movement of the slider. However, by forcing the slider upwardly as seen in Fig. 1, the pin or nubbin 31 will spring over the shoulders 27 and 28, allowing the slider to extend to the stop 17, thus freeing the stringer 11 from the slider and allowing both stringers to be quickly pulled apart.

Fasteners of the type and kind under consideration are desirable on certain types and kinds of installations where it is desirable to provide a quick separation of the stringers, and particularly on long stringers where time is required in moving a slider along the coupled scoops in separation of the stringer. For example, in mounting of interlinings in coats where the interlining is held in the coat by a separable fastener, extending along the coat front and over the shoulders and at the back of the neck. With my present quick separable fastener, a lining could be removed by simply forcing the slider to the stop, as at 17, and then the lining could be quickly pulled from the coat avoiding the necessity of operating the slider first along one side, across the shoulder and neck portions and then down the other side.

Fasteners of the type and kind under consideration are applied to what is commonly known "separable fasteners," where the other unshown end of the stringers have pin and box or other couplings for quick separation of the stringers, but as these structures are well known in the art, no illustration thereof is herein given. It is well to point out, however, that the slider is held against removal from one stringer, for example, the stringer 10. In other words, the conventional box part of the coupling is applied to the stringer 10 for this purpose.

The pin or nubbin 31 is preferably composed of a spring like material, and I have found that plastic materials are suitable for this purpose,

nylon type of plastics being one which is suitable. The pins or nubbins may be secured to the link or scoop 18 in any desired manner, regardless of whether the fastener is metal or of a plastic type. In plastic fasteners a suitable adhesive may be employed to adhere the parts together.

In Fig. 3 of the drawing is shown a slight modification in the type of stop pin or nubbin employed. Here the special stop link or scoop 18' has apertures 32 and 33 which extend to the bead 13' of a tape 11' and two pins or nubbins 34 and 35 are employed, one fitting in each of the apertures 32 and 33, and seating upon the beaded edge 13' of the tape. The pins or nubbins 34 and 35 will be of the same type and kind as the pin or nubbin 31.

In forming the scoops or links as die casting, the apertures as at 30 in the special link or scoop 18, and 32-33, as at 18', may be formed in the casting of the scoop and in one instance, a punch is employed to pierce the bead of the tape to form a single passage as at 30 through the link 18, whereas in the other instance, this operation is dispensed with and two pins or nubbins as at 34-35 are employed.

Considering Fig. 1 of the drawing, 36 represents the frog or web at the wide end 26 of the slider, which forms the diverging channels for guiding the scoops in coupling and uncoupling of the stringers. Considering now Fig. 2 of the drawing, it will appear that the top and bottom walls 22 and 23 have inturned side flanges 37 and 38 which retain the scoops in the channelled slider body. At 39 is shown part of the loop or coupling with which the conventional pull, not shown, is attached.

Having fully described my invention, what I claim as new and desire to secure by Letters Patent is:

1. A quick separable fastener comprising a pair of stringers, scoops on adjacent beaded edges of the stringers for coupling and uncoupling the same, the scoops of one stringer being greater in number, at one end, than the scoops of the companion stringer, said companion stringer at the corresponding end thereof having a stop element, said element having a pair of fingers adapted to be arranged between scoops of the first mentioned stringer, a slider for coupling and uncoupling said stringers, part of one side of the slider being recessed, a stop shoulder at one end of the recess, and said element having a yieldable nubbin normally engaging the shoulder of the slider in checking closing movement of the slider on said stringers and over which the shouldered portion of the slider is adapted to be forceably drawn in freeing the second stringer from the slider for quick separation from the first stringer.

2. A quick separable fastener comprising a pair of stringers, scoops on adjacent beaded edges of the stringers for coupling and uncoupling the same, the scoops of one stringer being greater in number, at one end, than the scoops of the companion stringer, said companion stringer at the corresponding end thereof having a stop element, said element having a pair of fingers adapted to be arranged between scoops of the first mentioned stringer, a slider for coupling and uncoupling said stringers, part of one side of the slider being recessed, a stop shoulder at one end of the recess, said element having a yieldable nubbin normally engaging the shoulder of the slider in checking closing movement of the slider on said stringers and over which the

shouldered portion of the slider is adapted to be forceably drawn in freeing the second stringer from the slider for quick separation from the first stringer, and another two fingered element on the second stringer outwardly of and adjacent said first element for guiding the slider as the latter is forceably drawn over said yieldable nubbin.

3. In quick separable stringers for separable fasteners, long and short stringers, the long stringer having a positive stop adjacent an end link of said stringer, a double-walled slider having side flanges for coupling and uncoupling the stringers, the short stringer having a stop link positioned thereon at a point beyond the slider when the latter is moved into engagement with the stop of the long stringer to provide free pull apart separation of the stringers, said stop link and slider having interengaging means for checking normal movement of the slider on the stringers at the point of location of the stop link on said short stringer, said means on said stop link comprising a plastic nubbin, said means on said slider comprising a projecting shoulder on the inner surface of each wall of the slider, said nubbin being exposed on opposed surfaces of said link, and said plastic nubbing being sufficiently yieldable as to enable the slider to be forceably drawn past the same.

4. A stop link for quick separable stringers of the character described, said link comprising an element arranged upon the beaded edge of a stringer tape, said element having a pair of scoop engaging fingers, and said element having a projecting nubbin of yieldable material in alignment with the beaded edge of the tape.

5. A stop link for quick separable stringers of the character described, said link comprising an element arranged upon the beaded edge of a stringer tape, said element having a pair of scoop engaging fingers, a bore in said element in alignment with a bore in the beaded edge of the tape, and a plastic nubbin secured in said bores and projecting beyond the surface of said element.

6. In separable fasteners employing stringers and a double-walled slider having side flanges, said slider being movable along the stringers to couple and uncouple said stringers, a stop element on the stringers intermediate stringer ends, said element being adapted to freely enter the slider, means on each wall of the slider for engaging said element to check normal movement of the slider along the stringers while permitting forceable movement of the slider over and beyond said stop element, said means on said slider comprising a projecting shoulder on the inner surface of each wall of the slider, and said stop element comprising a resilient bulk of nylon.

7. A stop element for stringers of the class described, comprising a die cast element arranged upon the beaded edge of a stringer tape, said element having a pair of fingers for receiving therebetween a stringer scoop of an opposed stringer, said element also having bores in alignment with the beaded edge of the tape and opening outwardly through opposed surfaces of said element, and plastic pin like members arranged in the bores of said element and projecting slightly beyond said opposed surfaces of the element.

8. A quick separable fastener according to claim 1 in which the yieldable nubbin is nylon.

9. A stop link according to claim 5 in which the plastic nubbin is nylon.

10. A stop element according to claim 7 in
which the plastic pin like members are nylon.
